James W. Harris.
 Inventor

UNITED STATES PATENT OFFICE.

JAMES WILSON HARRISS, OF CANTON, OHIO, ASSIGNEE TO ELBEL & CO., OF SAME PLACE.

DESIGN FOR A SNAP-HOOK.

SPECIFICATION forming part of Design No. 21,399, dated March 15, 1892.

Application filed November 12, 1891. Serial No. 411,760. Term of patent 7 years.

To all whom it may concern:

Be it known that I, JAMES WILSON HARRISS, a citizen of the United States, residing at Canton, in the county of Stark and State of Ohio, have invented a new and original Design for Snap-Hooks, of which the following is a specification.

The invention relates to a new and original design for snap-hooks.

The object of the present invention is to render snap-hooks ornamental and attractive. The invention resides in a snap-hook frame having an oval casing or socket-opening and a heart-shaped thumb-plate arranged within the casing or socket-opening, and these are the essential features of the design.

In the drawing, the figure is a perspective view of a snap-hook, showing my new design.

Referring to the drawing, 1 designates a snap-hook frame provided with an oval casing or socket-opening, in which is arranged a heart-shaped thumb-plate. These features form an ornamental and attractive snap-hook. 20

What I claim is—

The design for a snap-hook, as herein shown. 25

In testimony that I claim the foregoing as my own I have hereto affixed my signature in the presence of two witnesses.

JAMES WILSON HARRISS.
